UNITED STATES PATENT OFFICE.

LEVI HOLBEN, OF SAN FRANCISCO, CALIFORNIA.

AUTOMATIC FUEL-REGULATOR.

No. 867,042.

Specification of Letters Patent.

Patented Sept. 24, 1907.

Application filed January 22, 1907. Serial No. 353,442.

To all whom it may concern:

Be it known that I, LEVI HOLBEN, a citizen of the United States, residing at the city and county of San Francisco and State of California, have invented new 5 and useful Improvements in Automatic Fuel-Regulators, of which the following is a specification.

My invention relates to an apparatus for automatically regulating the amount of oil and steam which are supplied for combustion in furnaces.

10 It consists in the combination of parts and in details of construction which will be more fully explained by reference to the accompanying drawings, in which—

Figure 1 is a side elevation showing my invention in position. Fig. 2 is an enlarged section of a portion of the 15 apparatus. Fig. 3 is a view transversely just below the cylinder.

A is a bracket or support of any description which may be attached to the front of the boiler as at B, or upon any suitable or desired support in convenient 20 proximity to the boiler or furnace where the work is to be done. This bracket is here shown contrived to support a cylinder 2, in which a plunger 3 is fitted to reciprocate. This plunger is reduced as shown at 4, and continued in the form of a stem 5, which stem is slidable 25 through a screw-threaded sleeve 6, which serves as a guide to maintain the movements of the plunger in a direct line.

7 is a disk or plate having a hole through it, said hole being divergent at the upper side of the plate so as to fit 30 against the conical portion 4 between the piston and stem. This disk has a slot or channel made transversely across its lower face, and adapted to receive a bar which fits in the slot as shown at 8. This bar extends horizontally and has its end forked as shown at 9, and this fork 35 fits, and is slidable upon a rib or projection 10 of the bracket A; thus the disk 7 is prevented from turning. This disk has arms 11 and 11^a projecting from it at right angles from the line of the arm 8, and these arms carry 40 portions of the regulating mechanism to be hereafter described.

The office of the disk 7 and its interlocking bar 8 is to normally hold the arms 11 and 11^a in their proper position and to allow them to be reversed so as to project to the opposite side of the stem 5 when desired.

45 12 is a disk against which the upper end of a spring 13 fits and is seated. The lower end of this spring contacts with and is supported by a disk or plate 14 which is carried upon the upper end of the screw-threaded sleeve 6. This sleeve passes through the screw-threaded lower hub or boss 15 of the bracket A, and by turning 50 the screw-threaded portion the spring may be either compressed to increase its tension or relaxed, and the tension reduced for a purpose to be hereafter described.

To the ends of the arms 11—11^a, are connected the 55 upper ends of links 16—16^a; the lower ends of these links being made hollow and screw-threaded to re-

ceive a rod 17, the upper end of which may have a right and the lower end a left screw-thread. There are two of these rods 17—17^a, one connecting with each of the arms 11—11^a, and the lower ends of these 60 rods are connected with the crank or lever arms 18—18^a which serve to turn cocks 19—19^a controlling a passage through each of the pipes 20—20^a. These pipes supply oil and steam to a burner 21 and the proportions of oil and steam thus supplied are regulated by turning the rods 17 which, being right and left screw-threaded at opposite ends will, when turned in one direction, lengthen the distance between the levers 11—11^a and the levers 18—18^a and when turned in the opposite direction will correspondingly shorten the distance, so that the cocks 70 will be opened more or less according to the adjustment, and the proper proportion of steam and oil can be delicately regulated.

In order to move the plunger 3 within the cylinder 75 2, and thus move the arms 11—11^a and connected parts, I have shown a pipe 22 connected with the boiler so as to deliver steam into the upper part of the cylinder 2. If, for example, it be desired to carry 150 lbs. pressure of steam in the boiler, the 80 fire is so regulated that steam will be raised to such pressure in the boiler, and the tension of the spring 13 will be so regulated that until this pressure has been reached, it will prevent the piston or plunger from being forced down, and the adjustment of the rod 17 85 will so control the steam and oil cocks that the amount admitted will be sufficient to approximately maintain this pressure. If the pressure rises above the desired figure, the upward pressure of the spring 13 will be overcome by the downward pressure upon 90 the plunger 3, the spring 13 will be compressed and the arms 11—11^a caused to move downward with it, thus partially closing the cocks and reducing the fire so that the steam pressure will shortly be brought to the normal. If the pressure becomes reduced below 95 the desired figure, the pressure of the spring 13 will overcome that of the plunger 3, and the connected parts will be forced upwardly, thus opening the steam and oil supply cocks, and increasing the fire until the steam pressure in the boiler has again reached the 100 normal.

I have described this apparatus as being adapted to control a fire in which oil and steam are intermingled; but it will be obvious that the same device may be used to control an air supply under pressure in place 105 of or in conjunction with the steam pressure; and any other equivalent means for promoting the fire under the boiler to make steam which can be used in turn to regulate the supply.

One cock-controlling lever may have a little more 110 throw than the other, so that there will be a proportionate difference in the opening or closing of the

steam and oil cocks, to maintain a certain desired proportion of these elements delivered to the burner.

Having thus described my invention what I claim and desire to secure by Letters Patent is—

- 5 1. In an apparatus for the automatic control of fuel supply to boiler furnaces, a fixed cylinder having a plunger movable therein, a stem and guiding sleeve at the lower end, arms projecting outwardly from the junction of the stem with the plunger and movable in unison with said plunger, a disk having a transverse slot into which one of said arms is fitted, said arm having a guided fork at the upper end, a spring, disks surrounding the stem below said arm and between which the spring is located so as to press upwardly and retain the arms normally in their higher position, a screw thread cut upon the sleeve passing through a correspondingly threaded fixed nut whereby the lower spring supporting disk will be moved to increase or diminish the tension of the spring, means for admitting steam from the boiler into the upper end of the cylinder,
- 10 15 20 a structure with valve controlled steam and oil pipes lead-

ing thereto, and means between the spring and plunger controlled arms whereby the valves are opened or closed.

2. In an apparatus of the character described, a vertically disposed cylinder having a plunger movable therein and a guided stem, means for supplying steam from the boiler to the upper end of the cylinder to depress the plunger, an adjustable spring acting in opposition to the plunger, and means for regulating its adjustment, a transversely slotted disk against which the spring acts in opposition to the plunger pressure, an arm fitting the transverse slot having a guided fork at the outer end, arms projecting from the disk, a burner, means for supplying fluids under pressure to said burner, controlling cocks and connections between said cocks and the disk-carried arms, said arms being reversible in the slotted disk to transfer the mechanism to one side or the other of the cylinder axis.

In testimony whereof I have hereunto set my hand in presence of two subscribing witnesses.

LEVI HOLBEN.
